UNITED STATES PATENT OFFICE.

VALERIE NITECKI, OF PHILADELPHIA, PENNSYLVANIA.

DESIGN FOR A DRIP-PAN FOR REFRIGERATORS.

52,488.

Specification for Design.

Patented Sept. 24, 1918.

Application filed June 18, 1918. Serial No. 240,685. Term of patent 7 years.

To all whom it may concern:

Be it known that I, VALERIE NITECKI, a citizen of the United States, residing at Philadelphia, in the county of Philadelphia and State of Pennsylvania, have invented a new and original and ornamental Design for a Drip-Pan for Refrigerators, of which the following is a specification, reference being had to the accompanying drawing, forming a part thereof.

Figure 1 is a top plan view of the drip pan, and

Fig. 2 is a bottom plan view of the same.
I claim:

The ornamental design for a drip pan for refrigerators, as shown.

VALERIE NITECKI.
